ALONZO B. ELY, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

Application filed April 30, 1925. Serial No. 26,966.

To all whom it may concern:

Be it known that I, ALONZO B. ELY, a citizen of the United States, and resident of Groton, in the county of Tompkins and State of New York, have invented certain new and useful Improvements in Typewriting Machines (Case No. 193), of which the following is a specification.

This invention relates to improvements in typewriting machines, and more particularly to the line spacing mechanism thereof.

The principal objects of the invention are to provide a combined line spacing and carriage returning mechanism which will rotate the platen and return the platen carriage by a single operation without accidental overthrow or excessive rotation of the platen; to provide a simple, light and rugged line spacing and carriage returning mechanism for a low or flat portable typewriting machine of the three-quarter or semi-front strike class so constructed that it may be rapidly and easily operated without collision of the hand of the operator with other parts of the machine; to provide a line spacing mechanism having a horizontally swinging and vertically sliding hand lever of substantial proportions operating a horizontally swinging line space pawl formed integrally with a part of the lever and in which said lever exerts a thrust toward the right hand side of the machine directly against an abutment at the left hand end of the platen carriage during line spacing operations; to provide a line spacing mechanism including a horizontally swinging and vertically sliding hand lever having a fixed line space ratchet operating pawl thereon and means for positively arresting swinging and sliding movements of said lever when the pawl has carried one tooth of the ratchet around the desired distance with said pawl firmly engaged over the leading edge of the next succeeding tooth of the ratchet; to provide a swinging and sliding line space lever carrying a fixed pawl and also carrying an adjustable line space regulator for varying the extent of the return sliding movement of the lever to cause the pawl to rotate the line space ratchet one or two tooth spaces when next operated as may be desired; and to provide a simple and inexpensive line spacing and

carriage returning mechanism and supporting means therefor constructed substantially entirely of stamped sheet metal parts for quantity production and which is adjustable to compensate for inequalities in manufacture to insure proper coaction of the parts when assembled in a typewriting machine.

Other advantages of the invention will appear from the appended description in detail of the preferred embodiment thereof illustrated in the accompanying drawings.

In the drawings annexed, Fig. 1 is an end view of the platen carriage of the typewriting machine showing the line spacing and carriage returning mechanism thereon, the mechanism being shown adjusted for single spacing with the parts in returned or normal position;

Fig. 2 a front view, the parts being positioned as shown in Fig. 1;

Fig. 3 a plan view, the parts being positioned as shown in Figs. 1 and 2;

Fig. 4 a detail view showing the hand lever collapsed, said lever being collapsible for a purpose hereinafter set forth;

Fig. 5 a sectional view on the line 5—5 of Fig. 4;

Fig. 6 a view showing in perspective various parts of the line spacing mechanism detached, the line space regulator being shown rocked relatively to the rear portion of the lever on which it is pivoted to its position of adjustment for double spacing;

Fig. 7 a vertical sectional view of the machine on the line 7—7 of Fig. 8;

Fig. 8 a fragmentary plan view of the machine showing the parts at the end of a line spacing and carriage returning operation;

Fig. 9 a fragmentary end view of the line spacing mechanism with the parts positioned as shown in Figs. 7 and 8;

Fig. 10 a detail view showing the drop of the hand lever and pawl relatively to the ratchet when the regulator is rocked from the position shown in Fig. 1 to the position shown in Figs. 6 and 10 to adjust the line spacing mechanism for double spacing;

Fig. 11 a plan view of the machine, certain parts being omitted in order to more clearly illustrate the subject matter of the invention claimed herein; and

Fig. 12 a detail section on the line 12—12

of Fig. 11, showing the detent and detent-release means in normal position.

Only so much of the typewriting machine has been shown as is necessary to a full understanding of the present invention. The type bars 1 of the machine are pivoted on an arcuate pivot wire 2 in a type bar segment 3 rigidly secured to the main frame 4 of the machine in an upwardly and rearwardly inclined plane. The type bars when at rest extend upwardly and forwardly from their pivots and are supported by a suitable arcuate type rest 5. These type bars are actuated by suitable key-operated means to swing the bars to rearwardly and upwardly inclined printing positions in which the type thereon engage the platen roll 6 on its upper front quarter, as is usual in machines of the three-quarter or semi-front strike class.

The platen roll 6 is fixed on a platen shaft 7 extending through bearings 8 in the end plates of a platen carriage 9, the base plate of which is supported in a downward and rearward inclined plane on suitable anti-friction devices, as shown, to travel transversely of the machine on a carriage bed 10. The carriage bed 10 is supported on the main frame in a downwardly and rearwardly inclined plane to shift upwardly and rearwardly from its normal lower case position shown in Fig. 7 to an upper case position determined by the engagement of stops 11 on supporting and guiding brackets 12, fixed to the bed adjacent its ends, with stationary stops 13 held to the main frame, suitable anti-friction guiding means, as shown in Fig. 7, cooperating with said brackets to cause the carriage and bed to shift in a plane at a right angle to the plane of the bed and carriage base plate. Suitable finger wheels or platen knobs 14 are fixed on the ends of the platen shaft close to the outer faces of the carriage end plates. A pair of ribbon spools 15 are rotatably supported at opposite sides of the system of type bars on the brackets 16 held to the carriage bed adjacent opposite ends of the bed, said spools being housed in spool cups 17 attached to the brackets 16 and the spools and cups being located above the main frame forward of the path of travel of the carriage and at substantially the same horizontal level as the platen roll 6 and the forward ends of the end type bars of the type bar system. A rockable margin-stop-carrying bar 18 extends transversely of the machine between the end plates of the carriage in rear of and below the platen and is provided with reduced cylindrical end portions or trunnions 19 extending through bearing apertures in said end plates. Said bar is adapted to be rocked to release margin stops thereon by a suitable rock arm 82 fixed thereon.

The carriage is fed step-by-step from right to left by escapement dogs, not shown, cooperating with a rack 21 on the carriage and actuated by a type-bar-operated universal bar 20. Novel means are provided whereby the platen may be rotated for regular line spacing and the carriage returned through the medium of a line spacing lever either one line space at a time or two line spaces at a time, and also whereby the platen may be rotated in either direction for either regular line spacing or irregular line spacing, as may be desired, which means will now be described.

The main body portion of a sheet metal bracket 22 is rigidly held in an upright position by a pair of screws 23 flat against the outer face of the left hand end plate of the platen carriage 9 forward of the platen shaft, said screws passing through apertures 23^a in the bracket. An arm 24 extends downward and rearward from the main body of the bracket under the platen shaft and alongside the end plate and is formed with a horizontal outwardly projecting pierced ear or lug 25 at its rear end. A pair of superposed ears 26 and 27 project outwardly from the upper and lower ends, respectively, of the main body of the bracket, said ears lying flatwise in horizontal planes respectively above and below the horizontal plane of the platen shaft.

A cylindrical steel bearing post 28 extends down through an aperture 29 in ear 26 and has a reduced threaded lower end portion 28^a screwed through a threaded aperture 30 in ear 27. The apertures 29 and 30 are disposed one directly above the other in a line perpendicular to the base line of the machine frame so that said post extends vertically with its axis perpendicular to the axis of the platen and at an angle to the plane of the carriage base plate. The reduced threaded portion 28^a of the post is made sufficiently long to permit vertical adjustment of the post relatively to the bracket by screwing the post up or down, the post being locked in adjusted position by a lock nut 31 screwed on part 28^a tightly up against the under face of ear 27. The post is provided at its upper end with a head 28^b adapted to serve as a stop or abutment to limit sliding movement of the line space lever, as hereinafter described, said head being provided with a screw-driver receiving notch 28^c so that the post may be readily adjusted to vary the vertical plane of said head and also may be readily attached to and detached from its supporting bracket.

The line space lever swings horizontally about the post 28 and slides vertically on said post, said lever being stamped from sheet metal and formed at its rear end with a fulcrum section in the form of a vertical

yoke 32 the superposed end ears or members 33 and 34 of which extend inward in horizontal planes and are provided with bearing apertures 35 and 36, respectively, 5 through which post 28 extends. The flat upright body portion 32 of the yoke normally lies in a vertical plane extending directly fore and aft of the machine, swinging movement of the lever from right to left 10 being limited by engagement of a stop lug 37 extending rearward from ear 34 with the outer face of arm 24 of bracket 22.

The normal vertical position of the yoke-like fulcrum section of the lever on post 28 15 may be varied by means of a line space regulator comprising an angular sheet-metal stop lever pivotally held to the outer face of the vertical portion 32 of the yoke by a horizontal pivot screw 38 and having a forward- 20 ly extending arm 39 and a depending arm 40 having a curved cam edge 40^a at its lower end. Arm 39 of the regulator is formed with superposed horizontal lugs 41 at its forward end extending outwardly from its 25 upper and lower edges to form a convenient finger grip, and is formed at its upper and lower edges intermediate its ends with inwardly extending horizontal stop lugs 42 and 43. The lug 43 is located forward of lug 42 and is adapted to engage the forward edge of part 32 to arrest the regulator in the position shown in Figs. 6 and 10 in which the lower cam end 40^a of arm 40 is so disposed that ear 34 of the yoke portion 30 35 may drop down upon ear 27 of bracket 22. Lug 42 is adapted to engage the forward edge of part 32 to arrest the regulator in the position shown in Figs. 1, 2, 3 and 9, in which the arm 40 is vertical and its lower 40 end extends down below ear 34 of the yoke 45 and normally engages the top face of ear 27 of the bracket.

The line space lever is rocked from right to left by a coiled return spring 44 hooked 45 at one end in an eye 45 punched in part 32 near its rear edge and hooked at its other end in the pierced ear 25 on bracket arm 24. Eye 45 and ear 25 are so disposed that the spring extends downward and inward from eye 45 to ear 25 so as to exert a substantial rearward and inward pull on member 32 to swing the lever from right to left about the post and also to exert a substantial downward pull on said member to assist the action of gravity in quickly sliding said yoke member down the post after a line spacing operation. Said eye and ear are also so disposed that spring 44 will not engage the platen shaft during swinging and upward sliding line space movements of the lever. The cam end 40^a of arm 40 permits easy 50 rocking of the regulator from one position of adjustment to the other, and said regulator is securely but frictionally held in either 55 adjusted position by a friction washer 46

clamped between the regulator and the head of the regulator pivot screw 38.

A line space pawl 47 is formed integrally with ear 33 of the yoke portion of the lever and normally extends inwardly and slightly forward from the inner end of said ear across the plane of a sheet metal ratchet wheel 48 which is secured to the left hand end of the platen roll 6 by screws 49. The wheel 48 is spaced from the inner face of the 70 left hand end plate of carriage 9 and the pawl extends in front of the ratchet in either position of the regulator in a horizontal plane above the horizontal plane of the platen roll shaft and below the plane of the 75 highest part of the ratchet and preferably overhangs the upper front quarter of the ratchet, as shown. The upper front portion of the left hand end plate of the carriage is cut away as shown at 9^a to afford 80 clearance for the pawl and adjacent parts of the line space lever and permit the line spacing mechanism to be compactly arranged between the left hand end of the platen and the left hand platen knob 14 85 which is located close to the left hand end plate of the carriage, thus keeping the transverse dimensions of the machine down to a minimum. One important advantage 90 of the present construction is that it provides a portable machine having an easily operable line space lever of substantial proportions and in which an easily accessible left hand platen knob is provided without increasing the maximum width of the machine. 95

The finger-piece carrying arm of the line space lever in the particular embodiment of the invention illustrated is divided into two sections, the forward finger-piece carrying 105 section being foldable downwardly to compact the machine. This folding feature of the line space lever is claimed in my copending application Case No. 191.

The rear section 50 of the lever arm is 110 of angular form and is formed integrally with the fulcrum section of the lever, said section 50 comprising a flat metal strip bent upward from the forward edge of ear 33 of the fulcrum section into a vertical plane 115 parallel with the platen axis and then bent forwardly and downwardly into a horizontal plane and terminating at a point back of the vertical transverse plane of the rear-most portions of spool cups 17 to form a short forwardly extending arm portion. This horizontal portion of arm section 50 is formed with a depending ear 51 at its outer edge and a depending ear 52 at its inner edge 120 opposite the ear 51, said ears being located at the rear of the downwardly and rearwardly beveled stop edge 50^a of section 50. 125

The forward lever arm section is stamped from a single piece of sheet metal and is 130 formed at its rear end with a short hori-

zontal portion 53 extending under the horizontal portion of arm section 50 between ears 51 and 52; and formed at its outer edge with a depending ear 54 and at its inner edge with a depending ear 55 opposite ear 54, said ears 54 and 55 abutting the inner faces of ears 51 and 52 to prevent side play in the joint. The main portion 56 of the forward lever arm section is disposed in the lowest vertical position of the lever, in a horizontal plane slightly above the plane of the tops of the platen knobs and ribbon spool cups 17 from its forward end to a point at or slightly back of the vertical transverse plane of the rearmost portions of cups 17 where it is connected with portion 53 by a downwardly and rearwardly inclined stop portion 57 adapted to travel back of the left hand spool cup and normally engaged against the beveled stop edge 50^a of rear arm section 50.

The portion 56 of the lever is curved outwardly or toward the left from its rear end and is provided at its forward end with an integral upstanding finger piece 58, both the portion 56 and finger piece 58 being made dished or concavo-convex in cross-section, as shown, by a suitable pressing operation to stiffen the same and provide comfortable hand-engaging surfaces. The outward curve of part 56 prevents said part and finger piece from obstructing access to the platen in adjusting paper, making erasures, etc. The upturning of the finger piece and elevation of part 56 above the level of left hand knob 14, while the remaining portions of the lever and the regulator are disposed to the right of the fore-and-aft plane of said knob, permit ready access to the knob. The outcurve of the part 56 to the left of the fore-and-aft plane of its pivot also permits travel of finger piece 58 in an arc the chord of which is substantially parallel with the axis of the platen and the path of travel of the carriage, so that a maximum effective return thrust may be exerted on the carriage and so that there is little or no rearward thrust on the carriage during a line space and carriage return operation. All of these features are of particular importance in a small and light portable typewriting machine. Part 56 is of substantial length so that it travels over the left hand ribbon spool during endwise movements of the carriage with the finger piece located well forward with respect to the spools and type bars and at a convenient height for operation. The finger piece 58 is located in the same vertical fore-and-aft plane as the left hand platen knob 14 so that the left hand knob 14 may be easily grasped by passing the hand either under or to the left of the line space lever and so that the width of the machine is not materially increased by the line space lever.

A horizontal hinge pin 59 extends through an aperture 60 in ear 51 and through registering bearing apertures 61 and 62 in ears 54 and 55, and has a reduced threaded end portion 59^a screwed into a threaded aperture 63 in ear 52 to hold the pin in place. The foldable lever arm section 56 is locked in normal horizontal position by a ball detent 64 loosely projecting through an aperture 65 in ear 51 and partly projected into an aperture 66 in ear 54 by the free lower end of a flat spring 67 clamped at its upper end against the outer face of ear 54 by a screw 68. Aperture 66 is of smaller diameter than the ball. The lever may be collapsed by forcibly depressing the forward arm section thereof to force ball 64 out of aperture or socket 66, as shown in Figs. 4 and 5 and more fully described in my aforesaid copending application. Collapsing movement of part 56 is limited by engagement of ear 54 with a stop lug 69 bent inward from the forward edge of part 32 of the lever.

Swinging movement of the line space lever toward the right is limited by engagement of ear 54 (which acts as a stop in normal operation of the lever) with a forwardly and outwardly extending stop lug 70 on bracket 22. Lug 70 is permanently bendable laterally for purposes of adjustment to secure the proper point of arrest of the lever, said stop and stop lug 54 being adjusted to stop swinging of the lever toward the right simultaneously with engagement of ear 33 with the post head or adjustable stop 28^b to stop upward sliding movement of the lever, as shown in Figs. 7, 8 and 9. Pawl 47 is bendable permanently either up or down to insure proper coaction thereof with the ratchet wheel. This adjustment of the pawl may be made independently of or in conjunction with adjustment of the post 28 which is limited to an extent less than the thickness of ear 34 in order to prevent said ear from engaging under the shoulder on the post at the upper end of threaded part 28^a.

When the regulator is adjusted as shown in Figs. 1, 2, 3 and 9, operation of the line space lever will rotate the platen one full line space at a time. In this position of the regulator the pawl 47 is normally located at the level shown in dotted lines in Fig. 10 and in full lines in Figs. 1 and 2, and when the lever is rocked toward the right the pawl will first swing rearward into engagement with the ratchet tooth *b* and then will continue to swing back carrying the tooth *b* to the position previously occupied by the tooth *a*, the lever sliding upward on the post during this latter part of the swinging movement of the pawl so that the rigid pawl may follow the upward and rearward moving tooth *b* against which it is pushing.

As tooth *b* reaches the position formerly occupied by tooth *a* the stops 54 and 70 come into engagement and the ear 33 simultaneously engages against the post head 28^b, so that inward swinging and upward sliding of the lever are positively stopped with the rear edge of pawl 47 pressed against the following edge of tooth *b* and the leading edge of the next succeeding tooth *c* firmly engaged under the lower face of the pawl, all as shown in Figs. 7, 8 and 9. There is thus a jam lock of the parts which positively prevents overthrow or excessive rotation of the ratchet and platen. It will be noted that the leading edge of the pawl moves between positions substantially equal distances fore-and-aft of a transverse line through the axis of rotation of the pawl.

If it be desired to rotate the platen two full line spaces at a time, the regulator is rocked to the position shown in Fig. 10, whereupon the lever will slide down the post 28 under influence of gravity and spring 44 until ear 34 rests on bracket ear 27, the pawl dropping from the position shown in dotted lines to the position shown in full lines where it is closer to the ratchet and in front of the tooth *c*. If the lever is now rocked, the pawl will swing into engagement with tooth *c* and the lever and pawl will then rise as the swinging movement of the lever continues until tooth *c* has been moved to the position previously occupied by tooth *a*, whereupon the parts will jam in the same manner as above described with tooth *d* (Fig. 10) engaged under the pawl. The platen is thus rotated two full line spaces and locked against overthrow.

It will be noted that, owing to the shape and mounting of the lever and the arrangement of the parts, when ear 54 engages lug 70 during line spacing operations a substantially direct endwise thrust is transmitted directly from the lever to a fixed part on the carriage whereby the carriage is returned with an easy motion and the pawl and ratchet are relieved of injurious strain and excessive wear. When the lever is released after being rocked toward the right, the spring 44 aided by gravity will rock the lever toward the left until stop 37 engages bracket arm 24 and simultaneously slide the lever downward on the post until its downward movement is arrested by either the regulator stop arm 40 or the ear 34 engaging bracket ear 27, depending upon whether the regulator is set for single or double spacing. To prevent back lash of the ratchet and to insure proper positioning of the ratchet and platen and holding of the same against accidental movement with the printing line at the proper point I provide a suitable detent device.

The detent device comprises a swinging sheet metal arm 71 loosely pivoted at its

rear end on the left hand trunnion 19 of the margin stop bar 18 so as to swing independently of said bar, said arm extending forward and upward substantially tangential to the ratchet wheel 48 and carrying an inwardly extending trunnion 72 at its forward end on which is journalled a steel roller 73 normally yieldably held between two adjacent teeth of the ratchet by a coiled spring 74. The arm 71 lies in a plane 75 between the ratchet and the left hand end plate of the carriage which are closely adjacent, the arm having an upstanding finger 75 at its forward end confined between the ratchet and end plate and being confined 80 at its rear end between the end plate and margin release rock arm 82 to prevent undue side play of the arm and roller. A downwardly and rearwardly extending groove 76 is formed in the inner face of the left hand end plate of the carriage, said groove extending to the bottom of said plate opposite a notch or recess 77 cut out of the left hand end of the carriage base plate. A finger 78 extends downward and forward from arm 71 into said notch and the spring 74 is housed in said groove, the lower end of the spring being attached to said finger and the upper end of the spring being attached to the inner end of the uppermost fastening screw 23 of bracket 22 which projects into said groove near the upper end of the groove.

The arrangement of the detent device is such that the platen may be rotated for regular line spacing in either direction by turning the platen knobs. In order that the platen may be rotated in either direction for irregular or fractional line spacing, I provide a detent release device comprising a sheet metal lever 81 pivoted on a screw 79 at a point immediately above and intermediate the ends of arm 71, said lever being formed with a cam 80 extending forward from its pivot having a flat forward locking edge 80^a. The main body portion 81 of the lever normally extends downward and rearward and terminates in a suitable finger piece, said body portion of the lever normally resting on the top edge of arm 71, the lever being held in normal release position solely by gravity. By rocking the lever 81 upward and forward cam 80 will be caused to depress the roller carrying arm to free the roller 73 from the ratchet after which the flat edge 80^a of the cam will engage flat against the upper edge of arm 71 and the parts will be locked in detent releasing position. The platen may then be rotated in either direction any desired extent by turning the platen knobs. It will be noted that the detent and detent release means are of exceeding simple, inexpensive, light and compact construction and are compactly arranged with relation to the car- 130

riage and platen in such manner as to keep the width of the carriage at a minimum.

What I claim is:

1. In a typewriting machine, the combination of a platen carriage comprising base and end plates, means for supporting said carriage to travel transversely of the machine, in a rearwardly tilted position, a platen roll having a shaft journalled in and 10 extending through said carriage end plates, a pair of ribbon spools located forwardly of the path of travel of the carriage at substantially the same level as the platen roll, a line space ratchet wheel located between 15 the left hand end plate of the carriage and the adjacent end of the platen roll and held to rotate with said roll, finger wheels held to the ends of the platen roll shaft close to the outer faces of the end plates, a bracket 20 held against the outer face of the left hand end plate of the carriage and formed with a pair of superposed outwardly projecting ears in a vertical plane forward of the roll shaft and an arm extending rearwardly 25 under said shaft, a vertical bearing post stationarily supported in said ears and having a head located above the upper ear, a line space lever having a vertically disposed bearing portion formed with a pair of super- 30 posed ears located respectively above and below the upper bracket ear and through which said post loosely extends with its head normally spaced above the upper lever ear, said lever having a handle portion ex- 35 tending forwardly from its bearing portion and carrying an upstanding finger piece at its forward end, said handle portion extend- 40 ing rearwardly from the finger piece in a horizontal plane above the level of the finger wheels and ribbon spools to a point in the rear of the transverse plane of the rear edges of the spools, a fixed pawl extending inwardly from the bearing portion of the lever in front of the ratchet wheel, a coiled 45 return spring extending downward and rear- 50 wardly under the platen roll shaft and connected with the bearing portion of said lever and said bracket arm to rock the lever outward and slide it downward, a stop on the bearing portion of the lever adapted to 55 engage said bracket arm for arresting out- 60 ward swinging of the lever with the finger piece in the fore-and-aft plane of the left hand finger wheel, and cooperating stops on the bracket and handle portion of the lever 65 for arresting inward swinging of the lever after movement of the finger piece through an arc the chord of which is substantially parallel with the path of travel of the carriage, said post head being disposed to be engaged by the upper ear on the bearing portion of the lever to arrest upward sliding movement of the lever on the post simultaneously with arrest of inward swinging 70 of the lever, and said bracket and the bear- 75 ing portion of the lever being located inside of the plane of the inner face of the left hand finger wheel.
2. In a typewriting machine, the combination of a platen carriage, ribbon spools 70 located forward of the carriage, means sup- 75 porting the carriage to travel transversely of the machine, a platen roll having a shaft journalled in the carriage, a finger wheel on the left hand end of said roll shaft beyond 80 but close to the left hand end of the car- 85 rriage, a stationary vertical post held to the carriage in a fore-and-aft plane between the fore-and-aft planes of the finger wheel and left hand end of the carriage, a line 90 space lever slidably and pivotally held at its rear end to said post and having a nor- 95 mally outwardly and forwardly extending portion disposed horizontally in a plane 100 above the plane of the ribbon spools and finger wheel and provided at its forward end with an upstanding finger piece located in a vertical transverse plane forward of the plane of the rearmost parts of the spools, a ratchet wheel held to rotate with 105 the platen, a fixed pawl on said lever ex- 110 tending inwardly in front of said ratchet wheel, a spring for swinging said lever out- 115 wardly, means for arresting outward swinging of said lever with said finger piece substantially in the fore-and-aft plane of the finger wheel, and means for arresting inward swinging and upward sliding move- 120 ments of the lever after movement of the finger piece through an arc the chord of 125 which is substantially parallel with the path of travel of the carriage.
3. In a typewriting machine, the combi- 125 nation of a platen carriage, ribbon spools located forward of the carriage, means sup- 130 porting the carriage to travel transversely of the machine, a platen roll having a shaft journalled in the carriage, a finger wheel on the left hand end of said roll shaft beyond 135 but close to the left hand end of the car- 140 rriage, a stationary vertical post held to the carriage in a fore-and-aft plane between the fore-and-aft planes of the finger wheel and left hand end of the carriage, a line 145 space lever slidably and pivotally held at its rear end to said post and having an out- 150 wardly and forwardly extending portion disposed horizontally in a plane above the plane of the ribbon spools and finger wheel and provided at its forward end with an upstanding finger piece located in a vertical transverse plane forward of the plane of the rearmost parts of the spools, a ratchet 155 wheel held to rotate with the platen, a 160 fixed pawl on said lever extending inwardly in front of said ratchet wheel, a spring for 165 swinging said lever outwardly, means for arresting outward swinging of said lever with 170 said finger piece substantially in the fore-and-aft plane of the finger wheel, and 175

- means for arresting inward swinging and upward sliding movements of the lever after movement of the finger piece through an arc the chord of which is substantially 5 parallel with the path of travel of the carriage, said pawl and ratchet wheel and said lever arresting means being so arranged that said pawl will engage and push a tooth of the ratchet wheel to a predetermined point 10 during inward swinging and upward sliding of the lever and will be positively arrested when said tooth reaches said point with the next following tooth of the ratchet wheel engaged under the pawl.
- 15 4. In a typewriting machine, the combination of a platen carriage having end plates, a platen roll extending close to the left hand end plate of the carriage, a shaft on which said roll is mounted journalled in 20 and extending through the carriage end plates, a finger wheel on the left hand end of said shaft close to the outer face of the adjacent end plate of the carriage, a line space ratchet wheel located between the left 25 hand end plate of the carriage and the adjacent end of the platen roll and held to rotate with said roll, an arm pivotally supported at its rear end on the carriage and extending forwardly under the roll shaft 30 along the inner face of the left hand end plate of the carriage, a trunnion extending inwardly from the forward end of said arm under the ratchet wheel, a detent roller on 35 said trunnion, said left hand end plate having a groove in its inner face extending in an up-and-down direction, a coiled spring housed in said groove and secured at its upper end to the carriage and at its lower end to said arm and yieldingly urging said 40 roller between adjacent teeth of the ratchet wheel, and a lever and pawl device mounted on the carriage for rotating said ratchet and located substantially in its entirety between the fore-and-aft planes of said finger 45 and ratchet wheels.
5. In a typewriting machine, the combination of a platen carriage having end plates, a platen roll extending close to the left hand end plate of the carriage, a shaft on which said roll is mounted journalled in 50 and extending through the carriage end plates, a finger wheel on the left hand end of said shaft close to the outer face of the adjacent end plate of the carriage, a line space ratchet wheel located between the left 55 hand end plate of the carriage and the adjacent end of the platen roll and held to rotate with said roll, an arm pivotally supported at its rear end on the carriage and 60 extending forwardly under the roll shaft along the inner face of the left hand end plate of the carriage, a trunnion extending inwardly from the forward end of said arm under the ratchet wheel, a detent roller on 65 said trunnion, said left hand end plate hav-
- ing a groove in its inner face extending in an up-and-down direction, a coiled spring housed in said groove and secured at its upper end to the carriage and at its lower end to said arm and yieldingly urging said 70 roller between adjacent teeth of the ratchet wheel, a lever and pawl device mounted on the carriage for rotating said ratchet and located substantially in its entirety between the fore-and-aft planes of said finger and ratchet wheels, said pivoted roller carrying arm extending substantially tangentially to said ratchet wheel, and a detent roller release-lever pivotally held to the left hand end plate of the carriage against the inner 75 face of said plate having a rearwardly extending handle portion normally seated by gravity on the upper edge of said pivoted arm and provided with a cam portion forward of its pivot for depressing said arm upon upward and forward swinging of its handle portion.
6. In a typewriting machine, the combination of a platen carriage having end plates, a platen roll journalled in the end 80 plates of the carriage, a line space ratchet wheel located between one end of the platen roll and the adjacent end plate and held to rotate with the roll, said last mentioned plate having a groove in its inner face extending in an up-and-down direction, a pawl and lever mechanism for rotating said ratchet wheel, a bracket supporting said mechanism, screws for holding said bracket to the outer face of said grooved end plate 85 one of which projects into the upper end of said groove, a margin stop bar at the rear of the platen roll supported at its ends in the end plates of the carriage, an arm pivotally held at its rear end to said bar and 90 extending forwardly along the inner face of said grooved plate below the axis of the platen, a trunnion on said arm extending under the ratchet wheel, a detent roller on 95 said trunnion, a coiled spring housed in the 100 groove in said plate secured at its upper end to the bracket fastening screw projecting into said groove and connected at its lower end to said arm to yieldably urge the roller between teeth of said ratchet, a detent 105 release lever pivotally held to said grooved end plate above the pivoted arm and having a handle portion normally seated by gravity on said arm and a cam portion 110 adapted to depress said arm, said cam portion having a flat face adapted to engage the upper edge of the arm after the detent roller is freed from the ratchet wheel to lock the roller in released position.
7. In a typewriting machine, the combination of a platen carriage, a platen rotatably mounted on the carriage, means supporting the carriage to travel transversely of the machine, a ratchet wheel held to rotate with the platen adjacent the left hand 115 120 125 130

- end of the platen, a line-spacing and carriage-returning lever extending fore-and-aft of the machine, means supporting said lever at its rear end on the carriage adjacent the left hand end of the carriage for lateral swinging and vertical sliding movements relatively to the carriage, a fixed pawl on said lever extending inwardly in front of said ratchet wheel, a return spring for said lever, means for determining the position to which said lever is returned, and means for arresting inward swinging and upward sliding movements of said lever after said pawl has advanced a ratchet tooth to a predetermined point at which the under face of said pawl is engaged by the next following tooth of the ratchet wheel.
8. In a typewriting machine, the combination of a platen carriage, a platen rotatably mounted on the carriage, means supporting the carriage to travel transversely of the machine, a ratchet wheel held to rotate with the platen adjacent the left hand end of the platen, a line-spacing and carriage-returning lever extending fore-and-aft of the machine, means supporting said lever at its rear end on the carriage adjacent the left hand end of the carriage for lateral swinging and vertical sliding movements relatively to the carriage, a fixed pawl on said lever extending inwardly in front of said ratchet wheel, a return spring for said lever, means for arresting inward swinging and upward sliding movements of said lever after said pawl has advanced a ratchet tooth to a predetermined point at which the under face of said pawl is engaged by the next following tooth of the ratchet wheel, means for varying the initial level of the pawl relatively to the ratchet to cause the pawl to engage either of two successive ratchet teeth, and means for arresting outward swinging movements of the lever.
9. In a typewriting machine, a platen carriage, a platen journalled on the carriage, a ratchet wheel held to rotate with the platen, a line space lever, a fixed pawl on the lever for rotating the ratchet wheel and holding the same against overthrow, means for pivotally and slidably supporting the lever on the carriage, stop means limiting swinging movements of the lever to an arc of uniform length, means for varying the initial position of the lever lengthwise of its pivotal axis to position the pawl to engage either of two successive teeth of the ratchet, and means for arresting sliding movement of the lever when swinging movement of the lever in line-spacing direction is arrested with said fixed pawl obstructing advance movement of a tooth of the ratchet wheel.
10. In a typewriting machine, a platen carriage, a platen journalled on the carriage, a ratchet wheel held to rotate with the platen, a line space lever, a fixed pawl on the lever for rotating the ratchet wheel and holding the same against overthrow, means for pivotally and slidably supporting the lever on the carriage, stop means limiting swinging movements of the lever to an arc of uniform length, means for varying the initial position of the lever lengthwise of its pivotal axis to position the pawl to engage either of two successive teeth of the ratchet, and means for arresting sliding movement of the lever when swinging movement of the lever in line-spacing direction is arrested with said fixed pawl obstructing advance movement of a tooth of the ratchet wheel.
11. In a typewriting machine, a platen carriage, a platen journalled on the carriage, a ratchet wheel held to rotate with the platen, a line space lever, a fixed pawl on the lever for rotating the ratchet wheel and holding the same against overthrow, means for pivotally and slidably supporting the lever on the carriage, stop means limiting swinging movements of the lever to an arc of uniform length, means for varying the initial position of the lever lengthwise of its pivotal axis to position the pawl to engage either of two successive teeth of the ratchet, and means for arresting sliding movement of the lever when swinging movement of the lever in line-spacing direction is arrested with said fixed pawl obstructing advance movement of a tooth of the ratchet wheel.
12. In a typewriting machine, a platen carriage, a platen journalled on the carriage, a ratchet wheel held to rotate with the platen, a line space lever, a fixed pawl on the lever for rotating the ratchet wheel and holding the same against overthrow, means for pivotally and slidably supporting the lever on the carriage, stop means limiting swinging movements of the lever to an arc of uniform length, means for varying the initial position of the lever lengthwise of its pivotal axis to position the pawl to engage either of two successive teeth of the ratchet, means for arresting sliding movement of the lever when swinging movement of the lever in line-spacing direction is arrested with said fixed pawl obstructing advance movement of a tooth of the ratchet wheel, and a return spring arranged to simultaneously swing and slide said lever on its pivot to its starting point upon release of the lever after a line spacing operation thereof.
13. In a typewriting machine, a platen carriage, a platen journalled on the carriage, a ratchet wheel held to rotate with the platen, a line space lever, a fixed pawl

- on the lever for rotating the ratchet wheel and holding the same against overthrow, means for pivotally and slidably supporting the lever on the carriage, stop means 5 limiting swinging movements of the lever to an arc of uniform length, means for varying the initial position of the lever lengthwise of its pivotal axis to position the pawl to engage either of two successive teeth of the ratchet, and means for arresting inward swinging movements of the lever at a uniform point, and cooperating means on said lever and post for arresting upward sliding movements of the lever at a uniform point, said inward and upward movement limiting means being so disposed as to arrest the fixed pawl at a point at which its under face engages over a tooth of the ratchet wheel to positively 70 stop rotation of the ratchet wheel and platen. 75
- 10 16. In a typewriting machine, the combination of a platen carriage, a platen journaled in the carriage, a vertical bearing post on the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different 80 levels, cooperating stops on said lever and carriage forward of the transverse plane of said bearing post for arresting inward swinging movements of the lever at a uniform point, and said means for limiting outward and inward swinging of lever being 85 so disposed that the lever swings in an arc the chord of which is substantially parallel with the path of travel of the carriage. 90
- 15 17. In a typewriting machine, the combination of a platen carriage, a platen journaled in the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different 95 levels, and cooperating stops on said lever and carriage forward of the transverse plane of said bearing post for arresting inward swinging movements of the lever at a uniform point, said lever and pawl and said movement limiting means being so arranged that the leading edge of the pawl travels substantially equal distances for and aft of the transverse vertical plane of the bearing post and said lever swings through an arc 100
- 20 18. In a typewriting machine, the combination of a platen carriage, a platen journaled in the carriage, a vertical bearing post on the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different 105 levels, cooperating stops on said lever and carriage forward of the transverse plane of said bearing post for arresting inward swinging movements of the lever at a uniform point, and said means for limiting outward and inward swinging of lever being so disposed that the lever swings in an arc the chord of which is substantially parallel with the path of travel of the carriage. 110
- 25 19. In a typewriting machine, the combination of a platen carriage, a platen journaled in the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different 115 levels, and cooperating stops on said lever and carriage forward of the transverse plane of said bearing post for arresting inward swinging movements of the lever at a uniform point, said lever and pawl and said movement limiting means being so arranged that the leading edge of the pawl travels substantially equal distances for and aft of the transverse vertical plane of the bearing post and said lever swings through an arc 120
- 30 20. In a typewriting machine, the combination of a platen carriage, a platen journaled in the carriage, a vertical bearing post on the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different 125 levels, and cooperating stops on said lever and carriage forward of the transverse plane of said bearing post for arresting inward swinging movements of the lever at a uniform point, said lever and pawl and said movement limiting means being so arranged that the leading edge of the pawl travels substantially equal distances for and aft of the transverse vertical plane of the bearing post and said lever swings through an arc 130
- 35 21. In a typewriting machine, the combination of a platen carriage, a platen journaled in the carriage, a vertical bearing post on the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different levels, and cooperating stops on said lever and carriage forward of the transverse plane of said bearing post for arresting inward swinging movements of the lever at a uniform point, said lever and pawl and said movement limiting means being so arranged that the leading edge of the pawl travels substantially equal distances for and aft of the transverse vertical plane of the bearing post and said lever swings through an arc

the chord of which is substantially parallel with the path of travel of the carriage.

18. In a typewriting machine, the combination of a platen carriage, a platen journaled in the carriage, a vertical bearing post on the carriage adjacent the left hand end thereof, a ratchet wheel adjacent the left hand end of the platen and held to rotate therewith, a line space lever pivotally and slidably supported at its rear end on said post and having a forwardly extending handle portion, a fixed pawl extending inward from said lever in front of the ratchet wheel, cooperating stops on said lever and carriage for arresting outward swinging of the lever at a uniform point, cooperating stops on said lever and carriage relatively adjustable for varying the normal level of the lever and pawl to cause the pawl to engage ratchet teeth located at different levels, cooperating stops on said lever and carriage forward of the transverse plane of said bearing post for arresting inward swinging movements of the lever at a uniform point, and a coiled return spring connected at one end with the lever at a point outside of the fore-and-aft plane of the bearing post and extending downward and rearward and inward from said lever and connected at its other end with a fixed part on the carriage.

19. A line-spacing ratchet operating means comprising a bearing post support, a bearing post mounted on said support having a head at one end, a line-spacing lever having a yoke-like bearing portion slidably and pivotally held to said post, a line space pawl rigidly held to said lever, cooperating abutments on said lever and support for limiting the swinging movements of the lever to arcs of uniform length, one arm of the yoke portion of the lever cooperating with the post head to limit sliding movements of the lever when rocked in line-spacing direction and the other arm of said yoke portion being adapted to engage said post support to determine one initial starting point of sliding movement of the lever, and means on said yoke portion of the lever adjustable to engage said support and thereby prevent said last mentioned yoke arm from engaging the support to determine another initial starting point of sliding movement of the lever.

20. A line spacing ratchet operating means comprising a bearing post support, a bearing post mounted on said support having a head at one end, a line-spacing lever having a yoke-like bearing portion slidably and pivotally held to said post, a line-space pawl rigidly held to said lever, cooperating abutments on said lever and support for limiting the swinging movements of the lever to arcs of uniform length, one arm of the yoke portion of the lever cooperating

with the post head to limit sliding movements of the lever when rocked in line-spacing direction and the other arm of said yoke-portion being adapted to engage said post support to determine one initial starting point of sliding movement of the lever, means on said yoke portion of the lever adjustable to engage said support and thereby prevent said last mentioned yoke arm from engaging the support to determine another initial starting point of sliding movement of the lever, and means for adjusting the post axially relatively to the support.

21. A line spacing ratchet operating means comprising a bearing post support, a bearing post mounted on said support, an abutment member on said post, a line spacing lever having a yoke-like bearing portion slidably and pivotally held to said post, a line space pawl rigidly held to said lever, cooperating abutments on said lever and support for limiting the swinging movements of the lever to arcs of uniform length, one arm of the yoke portion of the lever cooperating with the abutment member on the post to limit sliding movements of the lever when rocked in line spacing direction and the other arm of said yoke portion being adapted to engage said post support to determine one initial starting point of sliding movement of the lever, means on said yoke portion of the lever adjustable to engage said support and thereby prevent said last mentioned yoke arm from engaging the support to determine another initial starting point of sliding movement of the lever, and a coiled return spring connected with said support and the yoke portion of the lever.

22. A line space ratchet operating means comprising a yoke-like sheet metal bracket adapted for attachment to a platen support, a bearing post extending through the arms of said bracket and stationarily held thereto, said post having a head at one end outside of said yoke bracket, a sheet metal line-spacing lever having a yoke-like bearing portion slidably and pivotally mounted on the post with its arms straddling the bracket arm nearest the post head, said lever having a handle portion perpendicular to the post provided with an integral stop lug adapted to engage the bracket for limiting swinging movement of the lever in line spacing direction, a ratchet operating pawl formed integrally with one arm of the yoke portion of the lever and extending therefrom substantially perpendicular to said post, a stop lug formed integrally with one arm of the yoke portion of the lever adapted to engage said bracket to limit return swing of the lever, the arm of the yoke portion of the lever nearest the post head cooperating with the head to limit sliding of the lever in

one direction, and a line-space regulator adjustably held to the yoke-portion of the lever shiftable to one position in which it limits sliding movement of said yoke portion away from the post head and to another position in which the arm of said yoke portion farthest from the post head engages said bracket arm farthest from the post head to limit such sliding movement 10 of the lever.

23. In a typewriting machine, the combination of a platen carriage, a platen journaled on the carriage, a ratchet wheel held to rotate with the platen adjacent the left hand end thereof, a sheet metal bracket held to the left hand end of the carriage provided with superposed spaced horizontal ears, a vertical bearing post held stationarily in said ears, a horizontally swinging sheet metal line-space lever having a vertically disposed yoke-like bearing portion at its rear end slidably and pivotally held to said post with its arms straddling the upper ear of the bracket and spaced therefrom, a pawl formed integrally with the upper arm of the bearing portion of the lever and extending inwardly in front of the ratchet wheel, a return spring connecting said bracket and bearing portion of the lever to swing the lever outwardly and slide it downwardly, means for arresting outward swinging of the lever at a uniform point, means whereby the normal vertical position of the lever may be varied, means 25 for arresting inward swinging of the lever at a uniform point, and means on said post cooperating with the upper arm of the bearing portion of the lever to arrest upward sliding of the lever at a uniform point.

24. In a typewriting machine, the combination of a platen carriage, a platen journaled on the carriage, a ratchet wheel held to rotate with the platen adjacent the left hand end thereof, a sheet metal bracket held to the left hand end of the carriage provided with superposed spaced horizontal ears, a vertical bearing post held stationarily in said ears, a horizontally swinging sheet metal line-space lever having a vertically disposed yoke like bearing portion at its rear end slidably and pivotally held to said post with its arms straddling the upper ear of the bracket and spaced therefrom, a pawl formed integrally with the upper arm of the bearing portion of the lever and extending inwardly in front of the ratchet wheel, a return spring connecting said bracket and bearing portion of the lever to swing the lever outwardly and slide it downwardly, an integral stop lug on the lower arm of the bearing portion of the lever adapted to engage the bracket to limit outward swinging of the lever, an integral lug on the forwardly extending arm of the lever adapted to engage the bracket to limit

inward swinging of the lever, a line-space regulator adjustably held to the bearing portion of the lever and shiftable between two positions in one of which the lower arm of said bearing portion is adapted to engage 70 the lower ear of the bracket to limit downward movement of the lever and in the other of which said regulator engages said bracket ear to arrest the lever in a higher position, and means on said post adapted to be engaged by the upper arm of the bearing portion of the lever to arrest upward movement of the lever.

25. In a portable typewriting machine the combination of a platen carriage, a platen 80 having a shaft journaled on the carriage, means supporting the carriage at a low level to travel transversely of the machine, ribbon spools located forward of the path of the travel of the carriage and at substantially the same level as the platen, a line space ratchet wheel adjacent the left hand end of the carriage held to rotate with the platen, a vertical bearing post held to the left hand end of the carriage forward of the platen shaft and in the rear of the spools, a line space lever having a vertical yoke-like bearing portion slidably and pivotally mounted on said post and adapted to travel behind the left hand spool and a forwardly extending horizontal handle portion connected with said yoke-like portion and disposed at a level above the spools and traveling over the left hand spool and provided with an upstanding finger piece at its forward end, 90 a fixed pawl on said lever extending inwardly in front of the ratchet wheel, and means independent of said pawl and ratchet wheel for arresting inward swinging of the lever.

26. In a portable typewriting machine, the combination of a platen carriage, a platen having a shaft journaled on the carriage, means supporting the carriage at a low level to travel transversely of the machine, ribbon spools located forward of the path of travel of the carriage and at substantially the same level as the platen, a line space ratchet wheel adjacent the left hand end of the carriage held to rotate with the platen, a vertical bearing post held to the left hand end of the carriage forward of the platen shaft and in the rear of the spools, a line space lever having a vertical yoke-like bearing portion slidably and pivotally mounted on said post and adapted to travel behind the left hand spool and a forwardly extending horizontal handle portion connected with said yoke-like portion and disposed at a level above the spools and traveling over the left hand spool and provided with an upstanding finger piece at its forward end, a fixed pawl on said lever extending inwardly in front of the ratchet wheel, and cooperating abutments on said carriage and lever forward 110 115 120 125 130

of said post for positively arresting inward swinging of the lever and transmitting endwise thrust toward the right to said carriage from said lever.

27. In a line spacing mechanism, the combination of a rotatably supported ratchet wheel, a combined line-spacing and overthrow preventing pawl cooperating with said wheel and normally extending across the edge thereof, a hand lever to which said pawl is rigidly held, means for supporting and guiding said lever so as to impart to said pawl a swinging movement about an axis perpendicular to the axis of the ratchet wheel and a motion of translation parallel with the axis of said swinging movement when the lever is actuated to engage the pawl with the ratchet, and means for preventing further pivotal and translational movement of the pawl after the same has engaged and advanced a ratchet tooth to a fixed point around the axis of the wheel at which the next following tooth of the ratchet wheel is engaged against the arrested pawl.

28. In a line spacing mechanism, the combination of a rotatably mounted ratchet wheel, a pawl extending across the wheel, means supporting said pawl for swinging movement and movement of translation about and along an axis perpendicular to the axis of the ratchet wheel, means for forcing said pawl against a tooth of the wheel to advance the wheel, and means for stopping pivotal and translational movement of the pawl when it has advanced said tooth to a predetermined point circumferentially of the wheel at which said pawl is engaged by the next following tooth of the wheel to obstruct further advance of the wheel.

29. In a typewriting machine, a traveling platen carriage, a platen journaled on the carriage, an arcuate system of type bars pivoted in an arc below and in front of the carriage and normally extending upward

and forward from their pivots and arranged to strike on the upper front quarter of the platen, a line space lever having an operating arm extending forwardly of the carriage at a level slightly above the level of the type carrying ends of the end bars of the type bar system and terminating in a finger piece at a point back of the type carrying ends of the bars, means operable by said lever to rotate the platen, and means supporting said lever on the carriage adjacent the left hand end of the carriage to swing toward the right and slide upwardly when actuated to operate the platen rotating means.

30. In a typewriting machine, a traveling platen carriage, a platen journaled on the carriage, an arcuate system of type bars pivotally supported at their rear ends to strike on the upper front quarter of the platen, a pair of ribbon spools supported at opposite sides of the system of type bars between the path of travel of the carriage and the vertical transverse plane of the free ends of the end bars of the type bar system, said spools and the forward ends of the end type bars being located at substantially the same level as the platen, a line space lever having an operating arm normally extending forwardly of the carriage at a level slightly above the level of said spools, and adapted to travel over the left hand spool, means operable by said lever to rotate the platen, and means pivotally and slidably supporting said lever on the carriage adjacent the left hand end of the carriage to swing toward the right and slide upwardly when actuated to operate said platen rotating means, whereby the clearance between the operating arm of the line space lever and the left hand spool and end type bars is increased upon a line space operation of the lever.

In testimony whereof I hereunto affix my signature.

ALONZO B. ELY.
